John T Davy, Troy, New York,
Letters Patent, No 182, dated May 30th
1848

The schedule referred to in these letters pa-
tent and making part of the same

To all to whom these presents shall come:

Be it known that I, John T Davy
of Troy, in the county of Rensselaer and
State of New York, have invented and
constructed a new ornamental design for
cooking stoves and that the following is
a full clear and exact description or charac-
ter which distinguishes it from all other things
before known, reference being had to the accom-
panying drawings thereof, in which fig 1. is a side
elevation, fig 2. is a front view of the stove.

The front of the stove has double doors above, in
summer arrangement with projecting panels (a)
with a foliated border, a portion of which is re-
presented at (b) there is a border around the top
plate of the stove, and also around the summer
arrangement, of leaf work, and the edges of all
the plates are surrounded by a border of points, foliated.
The side and front plates of the summer arra-
ngement

form a truncated pyramid (c) at the base surroun-
ded by a deep ogee shaped moulding (d) this
latter is ornamented with clusters of foliage (e),
as is also the ends of the base; the front of the base
has a lattice damper (f) extending nearly the
whole length thereof, and another damper of sim-
ilar form is placed at (g) above the summer ar-
rangement; both these dampers are ornamented
on the bars with scroll work. The side of the
stove has an oven door highly ornamented
with a flat top border and a centre piece of
foliage with a parrot and holding one of the
tendrils of foliage in its mouth; at the upper
front corner there is a fire door also with a flat-
top border and a centre piece of foliage; and
a similar group is placed under this door while
by its side and over the oven door is placed the name
of the stove, viz Washington after night. The legs
are formed of leaves, and terminate with ribs
at the bottom.

The above design for cooking stoves I claim as my
production and desire to secure the same by
letters patent
